UNITED STATES PATENT OFFICE.

SAMUEL NORRIS, OF BEDFORD, IOWA.

CHOPPING-KNIFE.

SPECIFICATION forming part of Letters Patent No. 534,570, dated February 19, 1895.

Application filed June 20, 1894. Serial No. 515,164. (No model.)

To all whom it may concern:

Be it known that I, SAMUEL NORRIS, a citizen of the United States, residing at Bedford, in the county of Taylor and State of Iowa, have 5 invented a new and useful Chopping-Knife, of which the following is a specification.

This invention relates to chopping knives, and it has for its object to effect certain improvements in knives of that character that 10 are employed for chopping or cutting meat into hash, chopping cabbage, potatoes and other vegetables, and also for cutting cakes, biscuit, &c.

To this end the main and primary object 15 of the present invention is to provide a simple and inexpensive chopping knife that shall be light and strong and possess efficient means for properly performing its different functions.

20 With these and other objects in view, which will readily appear as the nature of the invention is better understood, the same consists in the novel construction, combination, and arrangement of parts hereinafter more 25 fully described, illustrated, and claimed.

In the accompanying drawings:—Figure 1 is a perspective view of a knife constructed in accordance with this invention. Fig. 2 is a central vertical sectional view of the frame. 30 Fig. 3 is an enlarged detail sectional view on the line $x-x$ of Fig. 2.

Referring to the drawings, the numeral 1 designates a circular or cylindrical open knife-blade body that is made out of a single blank of sheet-steel. The knife blade body is cut to the desired size, being usually about three inches in diameter, and the two edges of the metal blank from which the knife is made are brought together at one 35 side into a single seam 2, and are soldered or otherwise suitably secured at this point to complete the true circular or cylindrical shape of the blade.

The circular blade body 1 is beveled at its 40 lower edge into the circular cutting edge 3, and from opposite sides and the upper edge of the blade body are extended upwardly the integral parallel attaching arms 4, be-

tween which and the upper edge of the body at both sides of said arms, the blade body is 50 cut into a shape to form substantially V-shaped open spaces 5, that are sufficiently large, and extend to a point sufficiently low, so as to facilitate the easy discharge of the material being cut, when it fills up the interior of the blade body, and thereby obviating 55 clogging of the same.

The upper extremities of the opposite integral parallel attaching arms 4 have securely fastened thereto the ends of the curved 60 handle strap or bail 6. The curved handle strap or bail 6 is preferably made of a strip of galvanized sheet iron of a width easily grasped by the hand, and the opposite side edges of the strap or bail are rolled into the 65 edge beads 7, that make the edges smooth so that the device can be comfortably manipulated. At its opposite ends the strap or bail 6 is provided with the parallel downturned attaching ends 8, against the outer sides of 70 which are secured the upper ends of the arms 4, by means of the securing rivets 9, and the upper fastened ends of the said arms 4, are tightly embraced or overlapped at their 75 side edges by the edge beads 7 of the handle strap or bail, so that the connection between these two parts is made more secure and firm, and is prevented from loosening on the rivets 9.

The herein described knife while being very 80 strong and very efficient for the several purposes to which it may be adapted, is at the same time light and easily manipulated, and the many other advantages of the same will readily suggest themselves to those skilled in 85 the art.

Having thus described the invention, what is claimed, and desired to be secured by Letters Patent, is—

In a knife of the class described, the combination of a circular blade body made of a single blank of metal and provided with a lower beveled cutting edge and opposite integral upwardly extending attaching arms forming at opposite sides thereof wide open 90 spaces communicating with the interior of 95

the blade body, and a curved handle strap or bail provided with downturned attaching ends secured to the upper extremities of the said attaching arms, and edge beads rolled 5 from its opposite side edges and adapted to tightly embrace or overlap the upper fastened ends of said securing arms, substantially as set forth.

In testimony that I claim the foregoing as my own I have hereto affixed my signature in 10 the presence of two witnesses.

SAMUEL NORRIS.
